US0D1082587S

(12) **United States Design Patent** (10) **Patent No.:** **US D1,082,587 S**
(45) **Date of Patent:** **** Jul. 8, 2025**

(54) **WATCH**

(71) Applicant: **TUDOR WATCH U.S.A., LLC**, New York, NY (US)

(72) Inventor: **Ander Ugarte**, Geneva (CH)

(73) Assignee: **TUDOR WATCH U.S.A., LLC**, New York, NY (US)

(**) Term: **15 Years**

(21) Appl. No.: **29/923,244**

(22) Filed: **Dec. 28, 2023**

Related U.S. Application Data

(62) Division of application No. 29/808,867, filed on Sep. 23, 2021, now Pat. No. Des. 1,016,626.

(30) **Foreign Application Priority Data**

Mar. 25, 2021 (CH) 145878

(51) **LOC (15) Cl.** **10-07**

(52) **U.S. Cl.**

USPC **D10/126**
